UNITED STATES PATENT OFFICE.

EUGENE J. FEELEY, OF FAIRFIELD, CONNECTICUT.

MAGNETIC SEPARATOR.

1,000,392.

Specification of Letters Patent. Patented Aug. 15, 1911.

Application filed February 18, 1911. Serial No. 609,383.

To all whom it may concern:

Be it known that I, EUGENE J. FEELEY, a citizen of the United States, and a resident of Fairfield, Connecticut, have invented certain new and useful Improvements in Magnetic Separators, of which the following is a specification accompanied by drawings.

This invention relates to magnetic separators, and the objects of the invention are to improve and simplify the construction of such machines, increase the efficiency, and increase the capacity of the machine by making the action more rapid.

15. Other objects of the invention are to reduce the wear and tear on the machine, avoid the use of a commutator and its attendant troubles, and reduce the dangers due to wear of insulation and accompanying 20 short circuits.

Further objects of the invention will hereinafter appear and the invention consists of a machine for carrying out all of the above 25 objects, embodying the features of construction, combinations of elements and arrangement of parts having the general mode of operation substantially as hereinafter fully described and claimed in this specification and shown in its preferred form in the accompanying drawings, in which—

Figure 1 is a side elevation partly in section of a machine embodying the invention; Fig. 2 is a longitudinal sectional elevation taken through the drum and connected 35 parts; and Fig. 3 is a detail diagrammatic view of the magnet frame and magnets.

Referring to the drawings, the machine is provided with any suitable frame shown in this instance comprising the uprights A 40 connected at the top by the longitudinal pieces B and the top bars C. At the bottom the uprights may be connected by the cross bolts D extending through suitable sleeves E arranged between the uprights.

45 A longitudinal bolt F within the sleeve G preferably connects the uprights at the back, thus providing a braced frame for the machine.

Suitable means in the form of bearing 50 brackets H are provided at the front of the frame and secured to the uprights A as by means of the bolts J. In the bearing brackets H is supported a shaft K which in this instance is adapted to be held stationary as by means of the set screws L. Revolvably mounted on the stationary shaft K

is a drum O of non-magnetic material, as thin sheet copper supported at either end upon spiders P and Q, preferably of brass. The spider Q as shown is provided with the 60 shoulder R having the sprocket wheel S over which passes the driving chain T for revolving the drum in the direction of the arrow U. Mounted within the drum O and stationary upon the shaft K is a segmental 65 magnet frame V. The magnet frame V is connected to the spiders W in any suitable manner, as by means of the screws X, and the spiders W are preferably pinned to the shaft K by means of the pins Y.

70 The magnet frame V is provided with longitudinal rows or series of staggered magnetic elements, preferably electro-magnets, the cores Z of which are suitably mounted on the frame as by means of the 75 reduced portions a secured in apertures in the frame. The magnet coils b are preferably so wound, that groups of longitudinal series or rows of magnets are of alternate polarity, as indicated by the plus and minus signs, in this instance two rows being shown 80 in a group. The circuit connections c are led to the magnet coils preferably through the aperture d in one end of the shaft K. According to this arrangement there is first 85 a longitudinal row of magnets with poles of one polarity, as negative; then another row of magnets with poles of the same polarity staggered between the magnets of the first negative row; then follows a row of 90 staggered positive magnets, and a second row of positive magnets staggered between the first row of positive magnets, then two rows of staggered negative magnets, and so on around the magnet frame. The said 95 poles are arranged in a plane so deviating from the line of free fall as to permit non-magnetic material to drop off, and means are provided as the drum O, for positively 100 moving material past said rows of magnetic elements.

105 The series of electro-magnets are preferably so located and arranged within the drum O, by means of the magnet frame, that they subtend an arc of at least 180° measuring in the direction of rotation of the drum O from a radius at the top of the drum slightly in advance of the vertical diameter of the drum, and the material to be separated is 110 preferably fed to the drum at a point at the top of the drum adjacent the first electro-magnet. In the drawing the magnet frame

V and the series of magnets are shown extending over an arc somewhat more than 180° for a purpose which will hereinafter appear. The material to be separated is 5 fed to the drum through the shaking chute *e* having the bottom plate *f* provided with an extension *g* which extends over the top of the drum into proximity with the first series of electro-magnets. The drum *O* is 10 preferably provided with longitudinal ridges or projections at intervals on its outer surface extending substantially the length of the drum. These longitudinal ridges are preferably in the form of fine brass wires *h* 15 soldered across the drum and preferably separated by arcs of substantially 90°.

In machines of this character, some of the magnetic material is held stationary in space, and the drum revolves between it and 20 the magnets. Some of the magnetic material will also be carried around on the drum. The wires carry the remainder of the material around and they also prevent a ridge or fringe of material from collecting 25 at the back of the drum, because they dislodge such ridge or fringe, which is held in space, and cause it to fall from the drum.

It has been found that in effect three separations are made in accordance with this invention, and to this end the collecting trough may conveniently be divided into three compartments, of which the section *A'* at the front collects the non-magnetic particles, as brass, the central section *B'*, located immediately forward of the vertical diameter of the drum collects a mixture of both brass and iron, while the rear section *C'* collects the magnetic particles, as iron. The mixture collected in the compartment *B'* may be run 40 through the machine again.

In the operation of the machine so far described, the drum *O* is revolved outside of the series of electro-magnets and the material to be separated comprising, for instance, a mixture of iron and brass chips, is 45 fed through the chute *e* and over the plate *f* and the extension *g*, to the top of the drum *O*. The electro-magnets are continuously energized and the iron chips are carried 50 around upon the surface of the drum as described while they remain within the field of force of the magnets, until they pass beyond the limits of the lines of force, at which point they fall by gravity within the receptacle provided. By providing series of 55 electro-magnets through an arc of at least or more than 180°, the iron chips are carried farther back from the vertical center line of the drum before they are deposited in a 60 receptacle and by this means more time is allowed and a greater opportunity afforded for foreign matter, which might be contained in the chips by reason of their roughness, to drop from the drum. The bulk of 65 the iron chips are therefore retained on the

drum for the maximum time required to the point where they drop by gravity. This arrangement of the magnets also allows the receiving box or receptacle for containing the iron chips to be larger, since it may be 70 placed to the rear of the drum. A larger pile of chips may therefore be collected before it is necessary to remove them, which is an advantage, especially in those cases where but one attendant is in charge of the 75 machine.

By winding the electro-magnets so that the series of magnets are of alternate polarity, the chips are compelled to rotate or turn substantially completely over while 80 passing through the influence of the magnet flux of the positive and negative poles, and while so rotating any brass or other non-magnetic materials are more readily liberated and fall by gravity from the drum at the 85 front. Any brass or other foreign matter which may be held by the roughness of the iron chips will be thrown off as the iron chips turn to meet the different magnetic poles, and the brass is collected in the receptacle beneath the machine as described. 90

By providing double rows of staggered magnets, each double row being of alternate polarity, I am not only enabled to obtain a rotation of the chips, but I produce a zig-zag motion of the particles in passing over the drum, which separates the masses longitudinally, and by thus opening the masses and agitating the particles, a much more complete separation of the magnetic and 95 non-magnetic particles is obtained than heretofore. Apparently, the fields of force extend in circumferential directions around the drum, and also at various angles across the drum, which is well shown by the continual arrangement and rearrangement of the particles in substantially geometric figures as they pass over the drum, thereby 100 shaking out the non-magnetic particles. 105

To aid the action of the magnets, and prevent the metal from adhering to the drum, the brass wires *h* of small diameter are placed across the entire length of the drum. The function of these wires is as described 110 to carry forward the metallic chips held in suspension and which would otherwise tend to creep up on the surface of the drum and also collect at the rear. The action of the drum is made more rapid by the wires and the capacity of the machine is increased. 115

Any suitable means may be provided for feeding material to the drum, but I have shown feeding mechanism which has been found to operate satisfactorily and well. The frame of the machine is preferably provided 120 with the cross bars *j* provided with the bearing brackets *k* suitably secured thereto as by means of the bolts *o*. A hopper *p* having feed adjuster *p'* is suitably mounted upon the frame and an agitator *q* mounted in bear- 125 130

ings on the bracket *k* is arranged within the lower portion of the hopper and provided with a driving pulley *r*. Above the lower lip *s* of the hopper is preferably arranged another agitator *t* suitably geared to the agitator *q*. The material passing from the hopper falls upon the shaker *e* which is mounted on the rollers *u*. The shaker *e* is actuated by eccentrics *v* on the driving shaft 10 *w* which is provided with a driving pulley *x* and main driving belt *y*. The driving sprocket *z* on the drive shaft *w* is connected by the driving chain to the drum sprocket. The pulley *m* on the drive shaft *w* is connected by the driving belt *n* to the pulley *r* of agitator *q*. The drive shaft *w* is suitably mounted in bearing brackets 2 connected to the frame by the bolts 3. The eccentrics *v* are provided with the eccentric straps 4 pivoted to which are the bolts 5 connected to the shaker *e*.

Rotation of the drive shaft *w* actuates the agitators *q* and *t*, and the shaker *e*, and also operates the driving chain *T* for the 25 drum *O*.

In accordance with this invention the electro-magnets are mounted upon a stationary frame within a revolving drum. The magnets are energized during the entire 30 time the machine is operating, so that commutator troubles are avoided and the danger of short circuits and wear on insulation. The construction of the machine is simplified and its life is prolonged. No wiper is 35 required to remove the chips from the drum

and the efficiency of the machine is greatly increased.

The particles and masses of particles are continually shaken and rotated or turned to effect separation, and the accumulation 40 of masses is prevented. When masses of particles fall upon the drum from the chute, they are drawn apart by the action of the fields of force extending at angles between the positive and negative poles of the staggered magnets to a much greater extent than when the magnets are arranged in circumferential lines, one opposite the other, around the drum.

I claim and desire to obtain by Letters 50 Patent the following:

In combination, a plurality of rows of magnetic elements, the poles of each row being arranged in staggered relation to the poles of adjacent rows, said rows being arranged in groups, the poles of each group being of the same polarity, and the polarity in each group being opposite to that of adjacent groups, said poles being in a plane so deviating from the line of free fall as to 55 permit non-magnetic material to drop off, and means for positively moving material past said rows of magnetic elements.

In testimony whereof I have signed this specification in the presence of two sub- 60 65 scribing witnesses.

EUGENE J. FEELEY.
